FLASH CAMERA

George Irwin, Highland Park, Ill., assignor to Imperial Camera Corp., Chicago, Ill., a corporation of Delaware

Filed May 19, 1966, Ser. No. 2,355

Term of patent 14 years

(Cl. D61—1)

Fig. 1

Fig. 2

Fig. 3

FIG. 1 is a side, top and front perspective view of a flash camera, showing my new design;

FIG. 2 is an opposite side elevational view;

FIG. 3 is a rear elevational view; and

FIG. 4 is a bottom plan view thereof.

Portions of the drawing figures are stippled to indicate contrast in appearance, and portions are diagonally lined to indicate transparency.

I claim:

The ornamental design for a flash camera, as shown and described.
